UNITED STATES PATENT OFFICE

JOSEPH C. LEWIS, OF MINERVA, OHIO, ASSIGNOR TO CHARLES W. KEPLINGER, RECEIVER OF THE AMERICAN ELECTRIC SWITCH CORPORATION, OF MINERVA, OHIO, A CORPORATION OF DELAWARE

ENTRANCE SWITCH AND SERVICE BOX

Application filed April 28, 1927. Serial No. 187,209.

This invention relates to improvements in entrance or service box construction such as is used at the entrance of an electric line into a building, and more particularly to the construction of the entrance switch 5 which is located within the box, and to the cooperation of the switch with the box whereby, regardless of the position of the switch, access cannot be had to the inside 10 of the box.

The object of the present invention is to improve the construction disclosed in the application of Joseph C. Lewis, Serial No. 44,609, now Patent No. 1,770,210, issued July 8, 1930, 15 by eliminating the bracket for supporting the switch handle and providing a rod extending entirely through the box for pivotally supporting the switch handle.

An embodiment of the invention is illustrated in the accompanying drawings, in which

Figure 1 is a plan elevation of the box showing the improved switch mechanism, the cover or door of the box being removed;

Fig. 2, a section on the line 2—2, Figure 1 showing the switch in closed position;

Fig. 3, a similar view showing the switch in open position;

Fig. 4, a transverse section on the line 30 4—4, Fig. 1;

Fig. 5, a detached perspective view of one of the links which connect the switch blades to the handle;

Fig. 6, a view similar to Fig. 1, showing a single blade switch constructed in accordance with the invention, and

Fig. 7, a perspective view of the improved switch box.

Similar numerals refer to similar parts throughout the drawings.

The box 1 is preferably formed of sheet metal and is of sufficient size to accommodate the switch block 2 and one or more 45 fuse blocks or the like. This switch block is formed of suitable insulation material and connected to the bottom of the box as by the screws 3.

Any desired arrangement of wiring may 50 be provided for upon the switch block and

either a single or multiple blade switch may be accommodated thereon.

In Figures 1 to 5 inclusive of the drawings a double blade switch is illustrated, the two switch blades 4 being each pivoted as at 5 upon a bracket 6 mounted upon the switch block, each blade being arranged to engage a pair of spring jaws 7 mounted upon the block. Stops 4^a and 7^a are punched from the blades and jaws respectively to limit the opening and closing movement of the blades.

A rod 8 is located through the box, at a point spaced above the bottom thereof, and connected to the side walls in any suitable manner as by riveting the ends of the rod thereto as shown at 9, or by the cotter pins 9^a and the switch handle or handles 10 are pivotally mounted upon this rod.

This handle is formed of insulation material and is provided with the reduced, peripheral portion 11, normally extending through the slot 12, in the door or cover 13, of the box, and having a radial stem 14, for manually operating the same.

Arcuate shoulders 15 are formed upon each side of the handle, to extend beyond each side of the slot 12, in the door or cover, in order to prevent access to the interior of the box, through said slot, regardless of the position of the handle. The inner side of the handle is recessed as at 17 for the connection of the link or links, generally indicated at 18, by which the handle is connected to the switch blades.

Where only one switch blade is used as in Figure 6, this link may be S-shaped, as illustrated in the application, Serial No. 44,609, above referred to, and where two switch blades are used, as illustrated in Figures 1 to 5 inclusive, the shape of the link is modified, the central portion of each half of the link being angularly located as indicated at 19, and having the angular ends 20 and 21 for pivotal connection to the handle and blades respectively.

The angular end 20 of the link extends into the recess 17 and is arranged to be pivotally connected to the handle as by the removable pin 22. The outer angular end 100

21 of the link is adapted to engage the stop shoulder 4^a to limit the opening movement of the switch blade, as shown in Figure 3, and the switch blade contacts with the stop shoulder 7^a, when the blade is in the closed position as shown in Figure 2, thus relieving the parts from strain.

10 The arcuate portion of the handle entirely closes the slot 13 in the door, at all times, thus preventing access to the interior of the box through this slot.

15 When it is desired to pack the box for shipping, in order to economize space, the pin 22 is removed, detaching the link from the switch handle, permitting the handle to be rotated upon the rod 8 into the position shown in broken lines in Figure 2, the link assuming the broken line position shown in this figure. The lid or door 13 may then 20 be closed tightly upon the box without any parts protruding therethrough, permitting the boxes to be stacked together in a minimum space.

25 From the above it will be evident that the construction is simplified and space within the box is economized by providing the rod 18, instead of the bracket shown in the application, for supporting the switch handle. This rod leaves the entire bottom 30 of the box free for the installation of fuse blocks or other necessary devices in the space occupied by this bracket in the application referred to.

I claim:

35 1. A sheet metal switch box provided with a slot, a switch block within the box, a switch blade pivotally mounted on the switch block, a rod located through the box and supported in the side walls thereof, and 40 an operating handle for the blade pivotally mounted upon the rod and located through the slot.

45 2. A sheet metal switch box provided with a slot, a switch block within the box, a switch blade pivotally mounted on the switch block, a rod located through the box and supported in the side walls thereof, and 50 an operating handle for the blade pivotally mounted upon the rod and located through the slot and arranged to entirely close the slot in all positions of the blade.

55 3. A sheet metal switch box provided with a slot, a switch block within the box, a switch blade pivotally mounted on the switch block, a rod located through the box and supported in the side walls thereof, and 60 an operating handle for the blade pivotally mounted upon the rod and having an arcuate portion located through the slot and closing the same in all positions.

65 4. A sheet metal switch box provided with a slot, a switch block within the box, a switch blade pivotally mounted on the switch block, a rod located through the box and supported in the side walls thereof, and

an operating handle for the blade pivotally mounted upon the rod and having an arcuate shouldered portion located through the slot and closing the same in all positions.

5. A sheet metal switch box, a door for the box provided with a slot, a switch block within the box, a switch blade pivotally mounted on the switch block, a blade-engaging jaw on the switch block, a rod located through the box and supported in the side walls thereof, an operating handle for the blade pivotally mounted upon the rod and located through the slot, and means on the switch blade and jaw for limiting the movement of the blade in either direction. 80

6. A sheet metal switch box, a door for the box provided with a slot, a switch block within the box, a switch blade pivotally mounted on the switch block, spring jaws on the switch block for receiving said blade, 85 a rod located through the box and supported in the side walls thereof, an operating handle for the blade pivotally mounted upon the rod and located through the slot, a rigid link pivotally connecting the handle to the blade, and the blade, link and jaws being arranged to cooperate to limit the opening and closing movements of the blade. 90

7. A sheet metal switch box, a door for the box provided with a slot, a switch blade pivotally mounted at one end within the box, a rod located through the box and supported at the side walls thereof, an operating handle for the blade pivotally mounted upon the rod and located through the slot, said handle having a recess therein, and a rigid link pivoted at one end within the recess of the handle and at the other end to an intermediate portion of the blade. 95

In testimony that I claim the above, I have hereunto subscribed my name.

JOSEPH C. LEWIS.
